LET-OFF MECHANISM FOR LOOMS

Application filed July 16, 1929. Serial No. 378,665.

This invention relates to let-off mechanisms for looms and more particularly such mechanisms of the positive let-off type.

During weaving operations the warp is subjected to a longitudinal stress or tension by the take-up mechanism which acts progressively to take up the cloth as it is woven, and such tension is subjected to a normal variation by the shed formation and beat-up which has been utilized heretofore to effect positive rotative movement of the warp beam to let off the warp as required by the fabric being woven. As the weaving proceeds, the diameter of warp on the beam gradually diminishes and it has been proposed heretofore to compensate for this by imparting increased rotative movement to the beam as the diameter of the warp decreases, thus letting off the warp from full to empty beam in response to the requirements of the particular fabric being woven.

Such let-off mechanisms have been practically successful for weaving certain kinds of fabrics, but the control of the let-off from the physical diameter of the warp on the beam is liable at times to let off too much, and at other times too little, with the result that the tension on the warp will vary from time to time and may be reflected in the finished cloth, especially where it is of the finer grades.

Instances of the above general character of positive let-off mechanisms are shown and described in the patents to Draper & Roper, No. 647,815, dated Apr. 17, 1900; Roper, No. 744,941, dated Nov. 24, 1903; and Roper, No. 843,181, dated Feb. 5, 1907, wherein the normal let-off is controlled from the whip roll through a train of speed reduction gearing, and compensation for the decrease in the diameter of the warp on the beam effected by a radius arm connecting the two members of a compound lever mechanism and movable relative thereto by a follower bearing upon the warp on the beam.

In let-off mechanisms of the above general type the warp passes from the warp beam over a yielding whip roll normally under the influence of spring means or its equivalent, and is consequently movable from its normal weaving position by variations in warp ten-

sion. The slight movement of the whip roll due to shed formation and the beat-up, which may be termed its "normal movement" has been utilized to let-off the warp as required by the fabric being woven, and with a beam of unvarying diameter the whip roll will maintain substantially the same position, variable only as stated, and the warp tension will remain substantially the same. As the warp on the beam gradually diminishes in diameter, however, the whip roll will be displaced a further amount and cause increased warp tension during the normal let-off. To insure substantially the same tension on the warp from full to empty beam the whip roll should be maintained in its normal weaving position, variable therefrom only by the beat-up and shedding operations, throughout the weaving operation.

One of the objects of the present invention, therefore, is to provide a positive let-off with means for maintaining the whip roll in substantially the same working position subject to its normal let-off movements that the warp may be subjected to substantially the same tension throughout the weaving operation from full to empty beam.

The present invention is a further development of the let-off mechanisms of the patents mentioned and in addition thereto provides means actuated from a going part of the loom and controlled by the whip roll for insuring a substantially uniform tension on the warp during weaving from full to empty beam.

The invention and novel features thereof will best be made clear from the following description and the accompanying drawings of one good form thereof.

In the drawings:

Fig. 1 is a side elevation, with some parts in section, showing a loom provided with the present invention;

Fig. 2 is an enlarged detail with parts broken away showing one form of means for moving the radius connection between the members of the compound pawl carrier;

Fig. 3 is an enlarged perspective detail with parts broken away, showing the compound pawl carrier and radius connection controlling means;

Fig. 4 is a sectional side elevation, showing the cam for controlling the position of the radius connection; and

Fig. 5 is a detail of the two-way acting pawl construction to be described.

The loom frame 1 may be of usual construction and has mounted thereon the crank shaft 2 connected by the pitman 3 to the lay 4, the swords 5 of which are mounted at the lower portion of the loom frame on the lay rocker 6.

The warp beam 7 having the large pinion 8 secured thereto and carried by bearings 9 in the loom frame, the rock shaft 10 extending transversely of the loom and having the arms 11 secured thereto, the whip roll 12 mounted in the arms 11, the rocker arm 13 secured to the rock shaft 10 and normally under the influence of spring means 14, the connected rod 15 secured to the rocker arm 13 and to the pawl setting lever 16 at 17, may all be of the same general construction as more fully and completely shown and described in the patents to which attention has been directed.

Pivotedly mounted on the bracket 18 at 19 is the downwardly extending pawl setter 16 having the channel-way 20, Fig. 3, and opposed to the pawl setter 16 is the pawl carrier 21 pivotally mounted at its lower end and preferably upon the drive shaft 22, and having the channelway or guide 23, and these parts may all be of the same general character as shown and described in the above-mentioned patents.

Mounted upon the pawl carrier 21 is the pawl 24 adapted to engage and actuate the ratchet 25, which is itself mounted upon the shaft 22, and connected to the gear 26 by a train of speed reduction gearing 27 for actuating the warp beam to let off the warp. These parts need no further description because they are all well shown and described in the prior patents and the details of these features form no part of the present invention.

Connecting the pawl setter 16 and the pawl carrier 21 is a radius connection 28, the position of which relative to the pawl setter and pawl carrier will determine the amplitude of pawl movement.

As also described in the patents mentioned, the pawl carrier 21 has a downwardly extending arm 29, the lower end of which is connected at 30 to a rod 31 having a slot 32 in its end portion embracing a pin 33 on a rocker arm 34 rising from the lay rock shaft 6.

From the construction thus far described and as pointed out in the prior patents, the warp will be subjected to normal variations in tension during weaving due to the shed formation and beat-up, and such variation in tension, which may be regarded as the normal weaving variation, actuates the pawl setter 16 to set the pawl back for engagement with another tooth of the ratchet, and on forward

movement of the lay the pawl is actuated to let-off the warp the normal amount required by the fabric being woven.

As the weaving continues, the diameter of the warp mass on the warp beam gradually decreases and the whip roll will be displaced from its proper weaving position in addition to its normal movement due to shedding and beat-up with a variation in the warp tension, and one of the purposes of the present invention is to provide means responsive to any such displacement of the whip roll and consequent variation of warp tension to effect return of the whip roll to its normal weaving position and restoration of the proper warp tension.

Mounted upon the loom frame is the bracket 35, one at each side of the loom, which supports the rock shaft 10, and the bracket 35 may be adjustable on the loom frame, as indicated, by the bolt and slot connection at 36. Extending from the bracket 35 is an arm 37 carrying a warp roll 38 over which the warp *a* passes from the warp beam, as indicated in Fig. 1, and then over the whip roll 12 and above the rock shaft 10 towards the front of the loom and the weaving instrumentalities.

Adjustably secured to the rocker arm 13 is a bracket 39, and extending downwardly from the bracket 39 but secured rigidly thereto is a controller arm 40. The controller arm 40 may be secured adjustably to the arm 39, as indicated at 41.

The lower end of the controller arm 40 is connected at 42 to a rod 43, which, as will presently appear, controls the operative condition of a going part of the loom to effect return of the whip roll to its initial or normal weaving position and change the let-off to accord with the diameter of the warp mass with consequent return of the normal warp tension.

The radius connection 28 is carried by a radius arm 44, Fig. 3, which is pivotally connected at 45 to a lever 46 pivotally mounted at 47 on a bracket 48 secured to the loom frame, and between its end portions the lever 46 rests upon, or is controlled by, a cam 49. In the present instance of the invention, the lever 46 carries a roll 50 which rests upon the cam 49.

The cam 49 is mounted upon the shaft 51, Fig. 2, and secured for rotative movement with the cam are the two ratchets 52 and 53, the teeth of which are oppositely directed, as clearly indicated in Fig. 2.

Pivotally mounted for rocking movement upon the shaft 51 is a pawl carrier 54, the lower end portion of which is connected at 55 to a rod 56 which may be conveniently operated from any going part of the loom, and, as shown in the present instance of the invention, the rod 56 is connected at 57 to the rocker arm 34 mounted on the lay rock

shaft, the construction being such that during the movements of the lay, the pawl carrier 54 will be rocked upon the shaft 51.

Secured to the upper end portion of the 5 pawl carrier 54 is a pin 58 on which is mounted the compound pawl, comprising the pawls 59 and 60, the former to act upon the teeth of the ratchet 52 when the pawl is in operative position, and the latter to act upon 10 the teeth of the ratchet 53 when it is operatively related thereto, the result being that when either one of the pawls 59 or 60 acts upon its associated ratchet it will serve to turn the cam 49 and thereby control the position 15 of the radius connection.

The operative or inoperative position of the pawls 59 and 60 is dictated by the controller arm 40 through a train of mechanism as will now be described.

20 Mounted for rocking movement on the pin 58 is the yoke 61, Fig. 2, having an elongated slot 62 into which projects a pin 63 projecting from the hub portion of the two pawls 59 and 60, as indicated in Fig. 5.

25 Threaded into the ends of the yoke 61 are the screws 64 and 65, the inner ends of which are at opposite sides of the pin 63, the result being that should the yoke 61 be rocked upon its pivotal support 58, the compound pawl 30 59, 60 will be moved to throw one or the other into action or both into a neutral position, depending upon the amplitude of movement of the controller arm 40.

35 As above stated, the controller arm 40 is connected to a rod 43 which, as indicated in Fig. 2, is itself connected to a pin 66 on the lower arm 67 of the yoke 61.

40 From the construction described it will be apparent that should the whip roll 12 be subjected to usual normal variations of position due to shed formation and the beat-up, the pawl and ratchet mechanism and combined pawl carrier will act to let-off the required amount of warp, usually one tooth of 45 the ratchet, but should the whip roll be further displaced due, for instance, to the decreasing diameter of the warp beam, the controller arm 40 will be moved to the right, Fig. 1, with the result that the pawl 60 will 50 be thrown into action and the cam 49 thereby rotated to permit a lower portion of the cam to come under the roll 50 of the lever 46, thereby lowering the radius connection and increasing the amplitude of pawl movement to 55 let-off additional warp and permit the whip roll to return to normal warp tensioning position, whereupon, the compound pawl mechanism will assume its central or inactive position and the warp beam will continue to be rotated under the lowered position of the radius connection to let-off the required amount of warp, due to the decreased size of the warp beam, while the normal tension of the warp will continue.

60 65 Should the whip roll displacement be mani-

fested by undue slackness of warp, again the controlling arm 40 will act by its movement to the left, Fig. 1, to throw the pawl 59 into action, thereby rotating the cam to lift the radius connection between the pawl setter 70 and the pawl carrier and decrease the amount of let-off and restore the whip roll to proper weaving position. Here again, when the amount of let-off has conformed to the character of fabric being woven and the 75 size of the warp mass on the beam and the whip roll has assumed its normal position, the compound pawl mechanism will assume its neutral position.

Thus the present invention provides that 80 during the weaving operation from full to empty warp beam, the warp tension will remain normal and be subjected, for the most part, at least, to normal variation only due to shedding and beat-up, and on the occurrence of any abnormal displacement of the 85 whip roll, the beam will be controlled to let-off warp to again bring the whip roll to proper weaving position and bring the warp tension back to normal. 90

It may be desirable in some cases to maintain the compound pawls 59 and 60 in the position to which they have been moved by the controller arm 40, at least, so that they will not too readily depart from their controlled position, and to this end the upper portion of the pawl carrier 54 had a yielding pin 68 which may pass through a lug 69 carried by the upper end of the pawl carrier 54. 100

The rounded head 70 of the yielding pin is adapted to bear upon one of the three surfaces carried by a lug 71 formed as part of the compound pawl 59 and 60. 105

What is claimed is:

1. In a let-off mechanism for looms, the combination of the warp beam, a yieldingly mounted whip roll, a ratchet and pawl for rotating the warp beam to let-off the warp, a pawl carrier and pawl setter fulcrumed at opposite ends, a radius connection between the pawl carrier and setter, means between the pawl setter and whip roll for setting the pawl responsive to normal variations in whip roll movement, and means connecting the radius connection and whip roll for changing the position of the radius connection responsive to abnormal variation in whip roll movement. 110

2. In a let-off mechanism for looms, the combination of the warp beam, a yieldingly mounted whip roll, a ratchet and pawl for rotating the warp beam to let off the warp, a compound pawl carrier comprising two members fulcrumed at their opposite ends, a relatively movable radius connection between the two members, means governed by normal variation in warp tension to move one of said members in setting the pawl, a controlling device connecting the whip roll and 115 120 125 130

the radius connection for changing the position of the radius connection between said members and consequently the amplitude of pawl movement responsive to abnormal variations in whip roll position, and means to move the set pawl to a fixed point.

3. In a let-off mechanism for looms, the combination of the warp beam, a yieldingly mounted whip roll, a ratchet to rotate the warp beam to let off the warp, a pawl carrier pivotally mounted at one end and having a pawl, a pawl setting lever pivoted at its opposite end, a radius connection between the two, connections between the setting lever and whip roll for setting the pawl under normal variations of warp tension, other connections between the whip roll and radius connection for moving the latter relative to the pawl carrier and setting lever in response to abnormal variations in whip roll position from full to empty beam for varying the amplitude of pawl carrier movement, and means to move the set pawl to a fixed point to let off the warp.

4. In a let-off mechanism for looms, the combination of the warp beam, a ratchet and pawl for rotating the beam to let-off the warp, a pawl carrier and a pawl setter pivotally mounted at opposite ends, a radius connection between the two, and means governed by the tension of the warp for moving the radius connection relatively to the pawl carrier and setter to change the amplitude of pawl carrier movement, and means for operating the pawl carrier.

5. In a let-off mechanism for looms, the combination of the warp beam, a whip roll, a ratchet operatively connected to the warp beam, a pawl carrier and pawl setter mounted for movement about different centres, a radius connection between the two, for rotating the warp beam to let-off the warp, means for setting the pawl responsive to normal variations in whip roll movement, and other means for varying the relative positions of the radius connection and the pawl carrier and setter and consequently the amplitude of pawl setting movement responsive to abnormal variations in whip roll movement from full to empty beam, and means for actuating the pawl to let-off the warp.

6. In a let-off mechanism for looms, the combination of the warp beam, a yieldingly mounted whip roll, a ratchet and pawl for rotating the warp beam to let-off the warp, a pawl carrier, a pawl setter connected to the whip roll, a shiftable connection between the pawl setter and pawl carrier for setting the pawl in response to normal variations in whip roll movement, and means governed by the whip roll for varying the position of the shiftable connection between the pawl carrier and pawl setter in response to abnormal variations in whip roll position, and

means for actuating the pawl to let-off the warp.

7. In a let-off mechanism for looms, the combination of the warp beam, a yieldingly mounted whip roll, a ratchet and pawl for turning the warp beam to let off the warp, a compound pawl carrier comprising two levers fulcrumed at opposite ends, a radius connection between the two, cam controlled means for varying the position of the radius connection, and means governed by the position of the whip roll for causing the cam controlled means to vary the position of the radius connection.

8. In a let-off mechanism for looms, the combination of the warp beam, a yieldingly mounted whip roll, a ratchet and pawl for turning the warp beam to let off the warp, a compound pawl carrier comprising two levers fulcrumed at opposite ends, a radius arm carrying a radius projection connecting the members of the pawl carrier, a cam for varying the position of the radius projection to increase or decrease the amplitude of pawl carrier movement, and connections from the whip roll for governing the position of the cam in response to variations in whip roll movement.

9. In a let-off mechanism for looms, the combination of the warp beam, a ratchet and pawl for turning the warp beam to let off the warp, a compound pawl carrier comprising two levers pivoted at opposite ends, a radius arm carrying a radius projection connecting the two levers, means for setting the pawl in response to normal variation in warp tension, a cam for controlling the radius arm and radius projection, means for operating the cam, a device movable in response to abnormal variations in whip roll position for controlling the cam operating means, and means for operating the pawl.

10. In a positive let-off mechanism for looms, the combination of the warp beam, means for positively rotating the warp beam to let off the warp including two members fulcrumed at opposite ends, means for actuating one of said members, a radius connection between the two members and movable relative thereto, and means controlled by variation in warp tension for moving the radius connection relative to the two fulcrumed members to increase or decrease the rotative movement of the warp beam.

11. In a let-off mechanism for looms, the combination of the warp beam, a yieldingly mounted whip roll, a ratchet and pawl and operating means for the latter for positively turning the warp beam to let-off the warp governed by normal movement of the whip roll due to shed formation and beat-up, other means actuated from a going part of the loom for maintaining the whip roll in normal weaving position, and devices controlled by any abnormal movement of the whip roll

for determining the operative or non-operative condition of said other means that the whip roll shall be returned to its normal position if abnormally displaced and thereby maintain the warp under substantially uniform tension.

12. In a positive let-off mechanism for looms, the combination of the warp beam, a whip roll, yielding means acting to hold the whip roll in normal weaving position with the warp under predetermined amount of tension, mechanism governed by normal movements of the whip roll for positively turning the warp beam to let-off the warp, means actuated from a going part of the loom for returning the whip roll to normal weaving position should it have been displaced therefrom so that the warp shall be maintained under the predetermined weaving tension, and devices connected to the whip roll for controlling the operative or inoperative condition of said means.

13. In a positive let-off mechanism for looms, the combination of the warp beam, a yieldingly mounted whip roll, a ratchet to rotate the warp beam to let-off the warp, a pawl carrier carrying a pawl, a pawl setter, a shiftable connection between the pawl carrier and setter for setting the pawl under normal variations of warp tension, mechanism for shifting the connection between the pawl carrier and setter to vary the amount of warp let-off from the warp beam under abnormal tension of the warp, and a controller connected to the whip roll for governing the operation of said mechanism in accordance with the abnormal tension on the warp.

40 In testimony whereof, I have signed my name to this specification.

CLARE H. DRAPER.
